UNITED STATES PATENT OFFICE.

WARREN B. BUCKLEY, OF OVERBROOK, PENNSYLVANIA.

DESIGN FOR A TIRE-TREAD.

51,546.

Specification for Design.

Patented Dec. 11, 1917.

Application filed October 15, 1917. Serial No. 196,765. Term of patent 14 years.

To all whom it may concern:

Be it known that I, WARREN B. BUCKLEY, a citizen of the United States, residing at Overbrook, in the county of Philadelphia and State of Pennsylvania, have invented a new, original, and ornamental Design for a Tire-Tread, of which the following is a specification, reference being had to the accompanying drawing, forming a part thereof, in which—

Figure 1 is a perspective view, and Fig. 2 is a plan view of a portion of a tire tread, showing my new design.

I claim:

The ornamental design for a tire tread, as shown.

WARREN B. BUCKLEY.
